UNITED STATES PATENT OFFICE

2,500,391

PIN CURL CLIP

Ruth K. Weaver, Chicago, and Loren M. Wing-blade, Mount Prospect, Ill., assignors to Gaylord Products, Incorporated, Chicago, Ill., a corporation of Delaware

Application December 24, 1948, Serial No. 67,132

4 Claims. (Cl. 132—46)

1

This invention relates to a pin curl clip of the type adapted for use in securing a spirally wound strand of hair.

It is an object of the present invention to provide a pin curl clip which is relatively simple and inexpensive to manufacture and which will not readily get out of order.

It is a further object of this invention to provide a pin curl clip consisting of a pair of hair clamping members pivotally connected intermediate their ends by means of a pair of resilient fingers formed on one of the members for engagement with laterally extending bosses formed on the other member, the resilient fingers acting to yieldably resist opening movement of the members.

This invention further contemplates the provision of a pin curl clip embodying a pair of members pivotally connected intermediate their ends to provide hair clamping portions and finger gripping portions, the hair clamping portions being normally in contacting engagement and movable to open position by means of the finger gripping portions.

This invention embodies other novel features, details of construction and arrangement of parts which are hereinafter set forth in the specification and claims, and illustrated in the accompanying drawing, wherein:

Fig. 1 is a top plan view illustrating a pin curl clip embodying features of the present invention.

Fig. 2 is a side elevational view of same.

Fig. 3 is a detail top plan view showing the upper clip member.

Fig. 4 is a side elevational view of same.

Fig. 5 is a detail top plan view showing the lower curl clip member.

Fig. 6 is a side elevational view of same.

Referring now to the drawing for a better understanding of this invention, the pin curl clip is shown as comprising an upper member 6 and a lower member 7 which are preferably blanked from resilient metal, such as high carbon steel. The upper member 6 is formed with an elongated hair clamping portion 8, an intermediate hinge portion 9 disposed at an angle of approximately 45° from the plane of the hair clamping portion 8, and a finger engaging portion 11 disposed in a plane substantially normal to the plane of the intermediate hinge portion 9. The forward end of the hair clamping portion 8 terminates in a pair of spaced, wedge-shaped fingers 12—12 which are inclined upwardly at an angle from the plane of the hair clamping portion 8. The intermediate pivot portion 9 is 55

2

formed with a pair of pivot bosses 13—13 which terminate in alignment with the side edges of the hair clamping portion 8. The hair clamping portion 8 is preferably formed with recesses 14 to decrease the weight of the upper member 6 and also to permit air to circulate through the clip members and a spirally wound lock of hair interposed therebetween.

The lower clip member 7 is formed with a hair clamping portion 16, a finger gripping portion 17 and a pair of resilient fingers 18—18, the fingers 18—18 projecting rearwardly from the hair clamping portion 16 along opposite sides of the finger gripping portion 17. The hair clamping portion 16 is preferably formed with a pair of spaced elongated fingers 19—19 having their forward ends pointed. The free ends of the resilient fingers 18—18 are formed arcuate at 21—21 to receive and engage their respective pivot bosses 13—13 formed on the upper member 6. In assembly of the upper and lower members 6 and 7, the pivot bosses 13—13 are inserted under the arcuate portions 21—21 of the resilient fingers 18—18. In opening or closing the hair clamping portions 8 and 16 of the members 6 and 7 respectively, it will be noted that the juncture point 22 of the pivot portion 9 and finger gripping portion 11 serves as a fulcrum for the member 6.

While this invention has been shown in but one form, it is obvious to those skilled in the art that it is not so limited but is susceptible of various changes and modifications without departing from the spirit and scope of the claimed invention.

We claim as our invention:

1. In a pin curl clip, an upper member comprising a hair clamping portion, an intermediate portion, a finger gripping portion, pivot bosses projecting outwardly from opposite side edges of said intermediate portion, said finger gripping portion being disposed in a plane substantially normal to the plane of said intermediate portion to provide a fulcrum edge for said upper member, a lower member comprising a hair clamping portion, a finger gripping portion, and a pair of resilient fingers projecting rearwardly from said hair clamping portion along opposite side edges of said finger gripping portion for engagement with said pivot bosses to yieldably resist pivotal opening movement of said upper member relative to said lower member, the free ends of said resilient fingers being bent into arcuate form to provide bearing surfaces to receive and prevent accidental displacement of the pivot bosses formed on the intermediate portion of said upper

member, the arcuately bent resilient fingers having a curve that is greater than the locus of the pivot bosses about the fulcrum.

2. In a pin curl clip, an upper member comprising a hair clamping portion, an intermediate portion, a finger gripping portion, pivot bosses projecting outwardly from opposite side edges of said intermediate portion, said finger gripping portion being disposed in a plane substantially normal to the plane of said intermediate portion to provide a fulcrum edge for said upper member, a lower member comprising a hair clamping portion, a finger gripping portion, and a pair of resilient fingers projecting rearwardly from said hair clamping portion along opposite side edges of said finger gripping portion for engagement with said pivot bosses to yieldably resist pivotal opening movement of said upper member relative to said lower member, the free ends of said resilient fingers being bent into arcuate form to provide bearing surfaces to receive and prevent accidental displacement of the pivot bosses formed on the intermediate portion of said upper member, the arcuately bent resilient fingers having a curve that is greater than the locus of the pivot bosses about the fulcrum, the hair clamping portion and finger gripping portion of said lower member being disposed in a common plane.

3. In a pin curl clip, an upper member comprising a hair clamping portion, an intermediate portion, a finger gripping portion, pivot bosses projecting outwardly from opposite side edges of said intermediate portion, said finger gripping portion being disposed in a plane substantially normal to the plane of said intermediate portion to provide a fulcrum edge for said upper member, a lower member comprising a hair clamping portion, a finger gripping portion, and a pair of resilient fingers projecting rearwardly from said hair clamping portion along opposite side edges of said finger gripping portion for engagement with said pivot bosses to yieldably resist pivotal opening movement of said upper member relative to said lower member, the free ends of said resilient fingers being bent into arcuate form to provide bearing surfaces to receive and prevent accidental displacement of the pivot bosses formed on the intermediate portion of said upper member, the arcuately bent resilient fingers having a curve that is greater than the locus of the pivot bosses about the fulcrum, the hair

clamping portion and finger gripping portion of said lower member being disposed in a common plane, the hair clamping portion of said lower member being bifurcated to provide a pair of elongated fingers arranged in spaced parallel relation.

4. In a pin curl clip, an upper member comprising a hair clamping portion, an intermediate portion, a finger gripping portion, pivot bosses projecting outwardly from opposite side edges of said intermediate portion, said finger gripping portion being disposed in a plane substantially normal to the plane of said intermediate portion to provide a fulcrum edge for said upper member, a lower member comprising a hair clamping portion, a finger gripping portion, and a pair of resilient fingers projecting rearwardly from said hair clamping portion along opposite side edges of said finger gripping portion for engagement with said pivot bosses to yieldably resist pivotal opening movement of said upper member relative to said lower member, the free ends of said resilient fingers being bent into arcuate form to provide bearing surfaces to receive and prevent accidental displacement of the pivot bosses formed on the intermediate portion of said upper member, the arcuately bent resilient fingers having a curve that is greater than the locus of the pivot bosses about the fulcrum, the hair clamping portion and finger gripping portion of said lower member being disposed in a common plane, the hair clamping portion of said lower member being bifurcated to provide a pair of elongated fingers arranged in spaced parallel relation, the hair clamping portion of said upper member being formed with a pair of wedge-shaped fingers inclined outwardly and upwardly from the plane of said hair clamping portion.
